Offield Reddick & Park Atty.

UNITED STATES PATENT OFFICE.

CLARENCE B. HARBISON, OF LIMA, OHIO, ASSIGNOR TO THE OHIO STEEL FOUNDRY COMPANY, OF LIMA, OHIO, A CORPORATION OF OHIO.

SIDE-FRAME STRUCTURE.

Application filed October 29, 1927. Serial No. 229,574.

This invention relates to improvements in side frames and more particularly to side frames of the ordinary hollow cast steel type having a journal box cast integral therewith.

5 The principal object of the invention is to provide an improved form of side frame of the type above described whereby increased strength and rigidity is afforded, especially adjacent the journal box.

10 As ordinarily constructed side frames of the type herein referred to are provided with tension and compression members converging at opposite ends adjacent the journal boxes. These tension and compression members are

15 usually formed of a curved channel or substantially oval cross section, either of the open C or closed D form. It has been found that many failures of such side frames occur through and adjacent the corner of the jour-

20 nal box, due to a combination of torsional and direct stresses thereon, and accordingly in the present invention I provide an improved box like cross section which is better suited to resist stresses at this point.

25 The invention may best be understood by reference to the accompanying drawings in which Figure 1 is a plan view showing one end of a side frame constructed in accordance with my invention,

30 Figure 2 is a longitudinal section of the portion of the frame shown in Figure 1,

Figure 3 is a transverse section taken either on line 3—3 or 3^a—3^a of Figure 2; and

Figure 4 is a section taken on line 4—4 of

35 Figure 2.

Referring to details shown in the drawings, the portion of the side frame illustrated in Figures 1 and 2 constitutes about one-half of an ordinary side frame, and includes upper 40 or compression member 10, lower or tension member 11, one upright column 12, and journal box 13, all formed in an integral casting as shown. The compression member 10 and the tension member 11 converge adjacent the 45 journal box in the usual manner.

In carrying out my invention I form the tension and compression members adjacent the column 12 of the usual standard curved or oval cross section as indicated in Figure 4,

50 but this form of section is merged into a box section as the tension and compression members approach the point of juncture with the

journal box, as shown in Figure 3, which figure represents the shape of the tension member 11, on line 3—3 of Figure 2, and also 55 the shape of the compression member 10 on line 3^a—3^a of the same figure. With a construction such as herein disclosed it will be seen that the compression and tension members merge into a single box like section 60 having a pair of relatively high upright side walls 14, 14, extending over and at the side of the journal box 13, thus giving far greater strength and rigidity at this point than with previous constructions in which the curved 65 or oval section of the compression and tension members were continued to the point of juncture with the journal box. Accordingly a side frame formed as above retains the demonstrated advantages of arcuate or oval 70 sections adjacent the column, but has also the additional advantage of greater strength adjacent the point of connection of the tension and compression members to the journal box due to the improved form of box 75 section as described.

While I have illustrated and described certain embodiments of my invention, it will be understood that I do not wish to be limited to the exact construction shown and described, 80 but that various changes and modifications may be made without departing from the spirit and scope of my invention.

I claim:

1. A side frame comprising an integral 85 casting including journal boxes, and tension and compression members converging at opposite ends adjacent said journal boxes, said tension and compression members each having arcuate cross sections intermediate 90 their ends merging into box sections adjacent each of said journal boxes.

2. A side frame comprising an integral 95 casting including journal boxes, and tension and compression members converging at opposite ends adjacent said journal boxes, said tension and compression members each having arcuate cross sections intermediate 100 their ends merging into box sections and in turn merging into a single box section adjacent each of said journal boxes.

Signed at Lima, Ohio, this 24th day of October, 1927.

CLARENCE B. HARBISON.
